W. FRIEDERICH.
MEDAL OR BADGE.

No. 18,902.

Patented Feb. 5, 1889.

Fig. 1.

Fig. 2.

UNITED STATES PATENT OFFICE.

WILLIAM FRIEDERICH, OF WASHINGTON, DISTRICT OF COLUMBIA.

DESIGN FOR A MEDAL OR BADGE.

SPECIFICATION forming part of Design No. 18,902, dated February 5, 1889.

Application filed January 14, 1889. Serial No. 296,347. Term of patent 3½ years.

To all whom it may concern:

Be it known that I, WILLIAM FRIEDERICH, a citizen of the United States, residing in Washington, District of Columbia, have invented and produced a new and original Design for a Badge or Medal, of which the following is a specification, reference being had to the accompanying photographs, forming part thereof.

10 Figure 1 is a representation showing the obverse of a medal or badge, and Fig. 2 the reverse.

15 The leading feature of my design consists in a circular medal or badge having upon its reverse an elliptical panel covering the central field, one of the foci of the said panel being nearer the periphery of the medal or badge than the other. Upon the obverse are two

smaller elliptical panels situated the one substantially in the upper left quadrant and the other in the lower right quadrant of the medal or badge. These latter panels are separated from each other by a scroll. A shield occupies the upper field of the medal or badge upon the obverse. Suitable portraits will be inserted in the panels upon the obverse and reverse, as well as dates, legends, and so forth; but these form no part of my design.

20 What I claim as of my invention is—

25 The design for a medal or badge, substantially as shown and described.

30 WILLIAM FRIEDERICH.

Witnesses:

A. J. SOLOMONS,
MYER COHEN.
